UNITED STATES PATENT OFFICE.

JOSEPH TOMLINSON, OF CHICAGO, ILLINOIS, ASSIGNOR TO COX MULTI-MAILER COMPANY, OF AUGUSTA, MAINE, A CORPORATION OF MAINE.

ADDRESSING, FOLDING, AND WRAPPING MACHINE.

1,105,315.

Specification of Letters Patent.

Patented July 28, 1914.

Application filed February 20, 1911. Serial No. 609,588.

To all whom it may concern:

Be it known that I, JOSEPH TOMLINSON, a citizen of the United States, residing at Chicago, in the county of Cook and State 5 of Illinois, have invented certain new and useful Improvements in Addressing, Folding, and Wrapping Machines, of which the following is a specification.

This invention relates to improvements 10 in addressing, folding and wrapping machines particularly adapted, though not necessarily limited in its use, for newspapers, periodicals and the like, and has for its primary object to provide an improved com- 15 bined addressing, folding and wrapping machine adapted to deliver the papers or other articles, addressed, with or without wrappers, and folded or unfolded; or to impart thereto one or more folds either 20 with or without an address, another object being the provision of an improved machine of this class which will be simple, durable and compact in construction and effective and efficient in operation.

25 A further object is the provision of an improved machine of this class having means whereby the address applying mechanism may be rendered inactive at will while the folding and wrapping mechanisms re- 30 main active.

A further object is to provide an im- 35 proved machine of this class having means whereby a wrapper may be supplied to the articles to be applied thereto, when the article is folded, and also means whereby the wrapper-supplying mechanism may be rendered inactive at will while the folding mechanism remains active.

40 A further object is to provide an im- proved machine of this class having means for receiving the article and conveying it away from the folding mechanism, to be delivered from the machine, and means whereby the article may be delivered to 45 the conveying mechanism to be thus conveyed away when the article is in any stage of its folded condition and at will.

A still further object is the provision of 50 an improved machine of this class having means whereby any one or more of the various mechanisms may be rendered inac- 55 tive at will, while the remaining mechanisms remain active.

To the attainment of these ends and the 55 accomplishment of other new and useful

objects as will appear, the invention consists in the features of novelty in the construction, combination and arrangement of the several parts hereinafter more fully described and claimed and shown in the accompanying drawings illustrating an embodiment of the invention, and in which—

Figure 1 is a view in elevation of one side of the machine and with parts omitted. Fig. 2 is a view in elevation of an improved machine of this character constructed in accordance with the principles of this invention and is taken from the right-hand side of Fig. 1. Fig. 3 is an elevation taken from the right-hand side of Fig. 2. Fig. 4 is a top plan view of Fig. 5, with some of the parts omitted. Fig. 5 is a sectional view on line 5—5, Fig. 4. Fig. 6 is a sectional view on line 6—6, Fig. 5. Fig. 7 is a sectional view on line 7—7, Fig. 5. Fig. 75 8 is a sectional view on line 8—8, Fig. 3. Fig. 9 is a detail sectional view on line 9—9, Fig. 5. Fig. 10 is a sectional view of the wrapper perforating rolls. Fig. 11 is an elevation of the pockets for receiving the article and wrapper, and for turning the article and wrapper to secure the flap of the wrapper. Fig. 12 is a detail sectional view on line 12—12, Fig. 1. Fig. 13 is a detail sectional view on line 13—13, Fig. 1.

Referring more particularly to the drawings and in the present exemplification of the invention the numeral 15 designates generally a supporting structure constituting the framework of the machine, and 16 (see particularly Figs. 1, 2 and 3) designates a supporting surface or platform which is adapted to receive the articles from an incline or chute 17. This platform 16 is preferably arranged near the top of the framework and is provided with a slot or opening 18 through which the paper when it is delivered in a flat condition upon the platform or table 16 is forced by means of 100 a folding blade or knife 19. This blade or knife is supported by means of an arm 20 pivoted as at 21 (see particularly Fig. 2). The arm 20 is adapted to be rocked around its pivotal support 21 in one direction by means of an elastic member 22 such as a coil spring or the like, which latter surrounds a rod 23 connected by one extremity to an extension 24 on the arm 20. The other end of the rod 23 passes through 110

22
a suitable guide 25 and is provided with a threaded extremity 26 to receive the nut or collar 27. This spring or elastic member 22 tends normally to throw the arm 20 in a direction about its point of pivotal support to cause the blade 19 to drop upon the paper lying upon the table 16 and when the blade strikes the paper it will fold the paper and force the fold through the opening 18. The arm 20 is adapted to be rocked 10 in the opposite direction to raise the blade 19 to permit another paper to be fed onto the table 16 in any suitable manner, preferably by means of a cam 28 (see Fig. 3) on the shaft 29 and this cam 28 engages an anti-friction roller 30 on an extension 31 on the arm 20. The extension 31^a is so arranged that the cam 28 when it engages the anti-friction roller 30, will rock the arm 20 about its point of pivotal support 21 in 20 a direction against the tension of the elastic member 22.

The shaft 29 receives its motion from what might be termed the main shaft 31 and 25 this shaft 31 receives its motion from any suitable power, preferably from a motor 32 (reference being had now more particularly to Figs. 1 and 2) mounted upon frame work. The shaft 33 of the motor is provided with 30 a gear 34 which meshes with an idle gear 35 having a gear 36 secured thereto and for rotation therewith. This gear 36 meshes with a gear 37 on a shaft 38. The gear 37 is mounted loosely upon a shaft 38 and is provided with a clutch face 39 adapted to cooperate with a clutch member 40 connected with a gear 41 and this gear 41 is secured to the shaft 38 for rotation therewith. The clutch elements 39, 40, are provided for a 40 purpose to be hereinafter set forth. The gear 41 meshes with a gear 42 on a shaft 43 for a purpose to be hereinafter set forth. The gear 37 transmits its motion to the shaft 31 through the medium of intermediate 45 gears, one of which gears 44 meshes with the gear 37 and also with a gear 45, the gear 45 in turn meshing with a gear 46 on the shaft 31. Thus it will be seen that when the motor 32 is operating all of the gears just described will be rotated as well as the shaft 50 31. The rotary motion of the shaft 31 is imparted to the shaft 29 through the medium of inter-meshing bevel gears 46 (see Fig. 3), one of which gears 46 is secured to the shaft 31 and the other is mounted loosely upon the shaft 29 and is provided with a clutch face 47. A clutch element 48^a co-operating with the clutch face 47 is secured to the shaft 29 for rotation therewith and is 55 adapted to be shifted longitudinally on the shaft to be moved into and out of active position with relation to the clutch element 47 to lock the gear 46 to the shaft 29 for rotation therewith and for releasing the gear 60 with respect to the shaft.

The articles may be fed to the table 16 from the incline or chute 17 in any desired or suitable manner. A suitable and efficient manner of thus supplying the articles will now be described and comprises a pair 70 of feeding rolls 48, (reference being now had more particularly to Fig. 1) arranged one above the other into the bite of which the paper is fed from the incline or chute 17. These rolls are adapted to grip the paper 75 and force it between the rolls and deliver it in a half fold upon the table 16. Motion may be imparted to these rolls in any suitable manner, preferably from the shaft 31 through the medium of the gear 46, which 80 gear meshes with an idler 49 and this idler 49 in turn meshes with a gear 50, which latter meshes with a gear 51. A gear 52 is connected with said gear 51 for rotation therewith and meshes with a gear 53. This gear 53 meshes with a gear 54 connected with one of the feed rolls 48 and also with a gear 55 which in turn meshes with a gear 56 connected with the other of the feed rolls 48. Thus it will be seen that the same 90 source of power may be employed for operating the feed rolls.

As the paper is fed upon the table 16, its feeding motion may be arrested by means of a stop 57 to position the paper with respect to the folding blade or knife 19. This stop 57 is adapted to be moved into and out of active position alternately with rejecting rolls 58, 59, and the stop is connected with the rolls 58, 59 for such operation in any 100 suitable manner, preferably by means of an arm 60 pivoted at 61 intermediate its ends and upon one end of which arm is mounted one of the rolls 58. The other end of the arm is connected to a crank arm 62, secured to a rock shaft 63 and this shaft 63 in turn is connected with a sleeve or collar 64 which supports the stop 57. This movement is imparted to the rolls 58, 59, and the stop 57 from a shaft 65 through the medium 110 of a cam 66, which latter engages one arm of a bell crank lever 67 and to the other arm of which lever is connected a link 68 which in turn is connected as at 69 with the arm 60. The specific construction and operation 115 of the ejecting rollers and stop 57 and the manner in which they operate alternately form no part of the subject matter of the present application but constitute a portion 120 of the subject matter of my co-pending application, Serial No. 603,658, to which application reference may be had for the description and operation of the parts not specifically described herein. Suffice it to say, however, that the ejecting rolls 58, 59, are 125 given a rotary motion through the medium of a train of gears 70, 71, 72, 73, 74, 75 and 76.

The rolls 58 and 59, are rendered inactive and the stop 57 maintained active preferably 130

by means which will now be described and which means also constitutes a portion of the above referred to application. A bar or rod 77 (see Figs. 1 and 2) is connected by one extremity with the arm 60 and the other extremity passes through a guide 78 and is threaded to receive a nut or collar 79. An elastic member 80 surrounds the bar or rod 77 between its point of connection with the arm 60 and the guide 78 and tends normally to exert its tension in a direction to move the roll 58 into operating position with respect to the roll 59. By elevating the roll 58 to its highest point and by tightening or screwing the nut or collar 79 on the extremity of the bar or rod 77 until it engages the guide 78, it will be apparent that the elastic member 80 will be prevented from exerting its tension to move the roller 58 toward the roller 59 and inasmuch as it will then be impossible for the roll 58 to be shifted by the cam 66, it will be manifest that the stop 57 will be held in an active position.

If desired, the papers may be supplied with an address and any suitable means may be provided for thus addressing the papers. A suitable and efficient mechanism especially adapted for this purpose is described and claimed in Patent No. 1,075,966, issued to Sandford C. Cox October 14, 1913, to which patent reference may be had for the specific construction and operation of such mechanism. However, this mechanism may be arranged in the present machine so as to apply an address to the papers after they have been delivered upon the table 16 and preferably before they have been given their quarter fold by the folding blade or knife 19, which fold, for the sake of convenience, will hereinafter be referred to as what is known in the trade as a "quarter fold." The address applying elements, one of which is designated by the reference numeral 81 in Fig. 1 may be supplied by the conveyer 82 to a proper position with respect to the paper on the table 16 and is adapted to be elevated in the manner set forth in the patent of Sandford C. Cox above referred to, by means of a cam on the shaft 65 and when in this elevated position, a stamper 83 is adapted to be lowered by means of another cam on the shaft 65 so as to strike the paper and force it into engagement with the address applying element 81 in the manner as set forth in both said application and said patent above referred to. After the address has been applied this stamper 83 is elevated and the folding blade or knife 19 lowered so as to strike the paper and force it through the opening 18 in the table 16 (see also Fig. 2).

As the folded portion of the paper passes through the opening 18 in the table 16, it passes into the bite of folding rolls 84 arranged beneath the table and which grip the

paper and draw it through the opening 18. From these rolls 84 the folded paper is passed between another pair of rolls 85 arranged preferably beneath the first pair of rolls 84 and spaced therefrom. A third pair 70 of folding rolls 86 is arranged beneath the second pair of rolls 85 and spaced therefrom and the last pair of rolls is adapted to receive the paper from the second pair. One of the rolls of each pair is preferably mounted in yielding bearings so that they may be adjusted with respect to the coöperating roll of the respective pairs to accommodate papers of various thicknesses and in order that the rolls, which are mounted in the yielding bearings, may be readily adjusted with relation to the respective rolls of the pair, an adjusting arm or lever 87^a is provided which is arranged in a convenient position for the operator and is connected in any desired or suitable manner to the adjustable rolls of the pairs whereby the latter may be adjusted at will. Motion is imparted to these folding rolls 84, 85, 86, from the shaft 29 through the medium of a gear 87 (see Fig. 2) which meshes with an idler 88, the latter in turn meshing with another idler 89. A gear 90 meshes with the idler 89 and also with a gear 91, which latter in turn meshes with a gear 92. The gears 91, 92, 90 respectively mesh with gears 93, 94 on the rolls of the pair 84 and also respectively mesh with gears 95, 96 on the rolls of the pair 85. These gears 95, 96, respectively mesh with idlers 97, 98, and these in turn 100 respectively mesh with gears 99, 100 on the rolls of the pair 86. The paper after it has reached this point in the machine will have been folded from the half-folded condition in which it was delivered upon the table 16 into a quarter-fold and may be delivered directly from the machine from this point in this condition, or a further fold may be given to the paper so that it may be delivered from the machine in what is known 105 as an eighth-fold.

As the delivery mechanism for receiving and conveying away the folded paper is the same whether the paper is folded into a quarter or an eighth fold, the mechanism 110 whereby the paper may be fed to the conveying and delivering mechanism in a quarter-fold will first be described, reference being had more particularly to Figs. 5 and 7. The rolls 86 preferably comprise a series of 115 spaced rolls as shown more clearly in Fig. 7 and arranged adjacent this pair of rolls is a series of guide plates 101, said guides being curved as shown and are adapted to project into the spaces between the adjacent 120 rolls. These guide plates 101 are each supported by means of an arm 102 which arms are secured to a rock shaft 103 in any desired or suitable manner and may be held in position with respect to the rock shaft by any 125 130

suitable fastening device 104. The shaft 103 is journaled in any suitable fixed portion of the frame and one extremity projects beyond the front of the supporting frame 15 as shown more clearly in Fig. 2 and an arm or handle 105 is secured to this projecting extremity of the shaft by means of which the shaft may be rocked. When it is desired to deliver the papers from the machine directly from the rolls 86 in a quarter-folded condition, the shaft 103 is rocked by means of the handle 105 so as to cause the guide plates 101 to assume the position shown in Fig. 5 so that the end or folded edge of the paper as it passes from the bite of the rolls 86 will strike the curved guides 101 and will deflect the end of the paper so that it will pass under the left hand roll 86 in Fig. 5 and between this roll 86 and a co-operating roll 106 which is journaled beneath the roll 86. Arranged on the side of the rolls 86, 106, opposite to that on which the guides 101 are arranged is another guide designated generally by the reference numeral 107 (see also Fig. 6) and this guide 107 is provided with bearings 108 through which a shaft 109 passes and the ends of this shaft have bearings in the framework of the machine. The guide 107 is provided with a flat face 110 along its upper side and the face 110 is so disposed that when the guide 107 is properly adjusted, the flat portion of the face will be arranged in line with the bite of the rolls 106, 86, so that when the paper is deflected by the guide 101 into the bite of these rollers, it will pass from between these rollers onto the flat portion 110 across the top of the guide 107. The upper face or the rear of the guide 107 is preferably curved downwardly as at 111 and this portion 111 co-incides with the face 110 to form a continuation of the surface over which the paper moves. From the guide 107 the paper passes between two endless conveyers 112, 113, one of which is arranged above the other and with one of the runs of one conveyor in close proximity to one of the runs of the other conveyor. These endless conveyers 112, 113 are preferably formed of tapes or flexible members and the receiving or forward end of the uppermost conveyor passes over the pulley 114 which is arranged in close proximity to the guide 107 and some distance in advance of the pulley 115 over which the forward end of the other conveyor 113 passes. It will thus be seen that when the paper passes from the guide 107, the end thereof will be presented between the runs of the endless conveyers 112, 113, which are in close proximity to each other and will be conveyed by these conveyers from the machine in the following manner. The endless conveyers are arranged with a substantially horizontal portion which first receives the paper and the rear portion of the conveyers are arranged

uprightly as shown in Fig. 2 and pass over suitable pulleys mounted upon a suitable support 116 forming an extension in the frame. The upright portions of the endless conveyers lead preferably to a point some distance above the top of the machine at which point the conveyer 112 passes over a pulley 117 and the conveyer 113 passes over a pulley 118, the latter being arranged preferably some distance above the pulley 117. Belt tighteners 119, 120, are provided for the endless conveyers. Extending across the top of the machine is an endless conveyer 121, one pulley 122 of which conveyer is located in close proximity to the upper extremities of the conveyers 112, 113, so that the papers when they are delivered from between the upper extremities of these conveyers will be discharged upon the conveyer 121 to be conveyed across the top of the machine to be discharged adjacent a support 122^a, which latter is provided for holding any suitable receptacle such as a bag or the like into which the papers are to be delivered. An intermediate pulley 123 may be provided for the conveyer 121 for supporting the latter. Motion may be imparted to the conveyers 112, 113, and to the conveyer 121 in any desired or suitable manner, but preferably from the shaft 29 as shown more clearly in Figs. 2 and 3. On this shaft 29 is arranged a sprocket wheel 124 over which a sprocket chain 125 passes and a sprocket wheel 126 is journaled upon the support 127 over which the other end of the sprocket chain 125 passes. A second sprocket wheel (not shown) is connected with the sprocket wheel 126 for rotation therewith and a sprocket chain 128 passes over this second sprocket wheel and also over a sprocket wheel 128^a. A gear 129 is connected with the pulley 117 and meshes with an idle gear 130 which in turn meshes with a gear 131 and the latter gear meshes with a gear 132 on the pulley 118 of the endless conveyer 113. A gear 133 is secured for rotation with the gear 130 and this gear 133 in turn meshes with a gear 134 which is secured for rotation with this sprocket wheel 128^a. Thus it will be seen that when the shaft 29 is rotated, motion will be imparted by means of the sprocket chains 125, 128, to the gear 134 and this gear will in turn impart motion to the endless conveyers 112, 113 and 121. A belt tightener 135 may be provided for the conveyer 121.

In order to prevent the forward edge of the paper as it passes over the guide 107 from striking the forward end of the endless conveyer 112 and being deflected upwardly between the end of the conveyer 112 and the roll 86, and further, in order to properly direct the paper over the guide 107 to the endless conveyers, additional guides 136 are provided, which guides are arranged

between the forward portions of the conveyor tapes 112 and the roll 86, and these guides 136 are supported by a shaft 137 (see also Fig. 6). Thus it will be seen that if the forward or folded end of the paper as it passes from the bite of the rollers and onto the guide 107 has a tendency to deflect upwardly, it will strike the guides 136 which latter will hold the end from curling upward and will cause the paper to be properly directed to the conveyers 112, 113. Thus it will be seen that when it is desired to give to the papers a quarter fold, the guides 101 and 107 must be adjusted to the positions shown in Fig. 5. The manner of adjusting the guide 107 into or out of the position shown in Fig. 5 will be presently described.

Should the occasion require and it is desired that the papers shall not be ejected or delivered from the machine in a quarter-folded condition, but it is desired instead to impart another fold to the thus folded paper so that it will be folded into what is known to the trade as an eighth fold, this additional fold is effected in a manner which will now be described. In order therefore to fold the paper into an eighth fold, the guides 101 must be adjusted from the position shown in full lines in Fig. 5 to that shown in dotted lines so as to move the guide plates 101 out of the path of movement of the advancing quarter-folded paper. This is accomplished by rocking the shaft 103 by means of the handle 105 so as to drop the guide plates 101 to permit the papers to continue downwardly from between the rolls 86 without being deflected between the left hand roll 86 and the roll 106.

As the papers are fed between the pairs of rolls 84, 85, 86, they will continue downwardly a predetermined distance and when they have reached the limit of this downward movement, the paper will be struck intermediate its ends by a second folding knife or blade 138 (reference being now had more particularly to Figs. 2, 5 and 8). Assuming that it is desired to deliver the papers from the machine after they have been given their "eighth fold" the guide 107 is permitted to remain in the position shown in Fig. 5 so that when the knife or blade 138 strikes the paper intermediate its edges, the paper will be deflected so that the folded edge will be presented to the bite of the rolls 106, 86, and these rolls will grip the paper and feed it over the face 110, 111, of the guide 107 to the conveyers 112, 113, which latter will receive and deliver the paper in its eighth fold condition from the machine in the manner as has already been described. In order to effect this action of the knife or blade 138 at the proper time, suitable mechanism must be provided for imparting motion, preferably a reciproca-

tory motion, to the knife or blade which will now be described. A cross head 139 is provided to which the knife or blade 138 is secured and is supported by means of links 140 which are journaled to move about a suitable axle 141. A lever 142 is pivoted intermediate its ends, preferably to the shaft 21 and is connected at one end to the link 140 in any suitable manner, preferably by means of a link 143. This link 143 is pivotally connected by one end as at 144 to the link 140 and by its other end as at 145 to the lever 142 so that when the lever 142 is rocked about its point of pivotal support, the link 143 will cause the link 140 to be moved about its point of pivotal support 141 to advance or retract the knife or blade 138. The lever 142 is preferably rocked by means of a cam 146 on the shaft 29, which cam engages an anti-friction roller 147 on the end 148 of the lever 142. It will thus be seen that when the shaft 29 is rotated the cam 146 will be rotated and will tend to move the lever 142 to retract the knife or blade 138. A forward movement is imparted to the knife or blade 138 to cause it to strike and fold the paper preferably by means of an elastic member 149 which surrounds a bar or rod 150, which latter is connected by one extremity as at 151 with the link 140 and the other end passes through a guide 152 and is threaded as at 153. The elastic member 149 is arranged between the guide 152 and the link 140 and tends normally to exert its tension in a direction to force the knife or blade 138 forwardly toward the paper and also tends to hold the anti-friction roller 147 in close proximity to the periphery of the cam 146 so that when the cam is rotated and the lever 142 is rocked thereby, the cam will rock the lever against the tension of the elastic member 149. A nut or collar 154 is provided on the threaded extremity 153 of the bar or rod 150 and serves as a means whereby the knife or blade 138 may be held in its retracted position against the tension of the elastic member 149, by being screwed upon a threaded extremity of the bar or rod 150 until it is in engagement with the guide 152. It will be manifest that inasmuch as the shaft 29 must be rotated to impart motion to the pairs of rolls 84, 85, 86, as well as other portions of the mechanisms, unless this second knife or blade 138 is rendered inactive when it is not desired to fold the paper into an eighth fold, it would strike the guides 101 when the latter are adjusted so as to conduct the papers from the machine in a quarter-folded condition, and thereby cause damage. Therefore this second knife or blade 138 must be prevented from acting and this may be accomplished by adjusting the nut or collar 154 in the manner just described. Obviously and as has been before explained when it is desired

to fold the papers into an eighth fold, the guides 101 are moved out of the way or out of the path of movement of the knife or blade 138.

It is thought that from the above description, the operation of the mechanism thus far described to perform the two functions, to wit, of folding the paper into a quarter-fold and delivering it from the machine in this condition, and of folding the paper into an eighth fold, and delivering it in this condition from the machine, will be clearly understood.

It has already been stated that when the papers are delivered in a half-folded condition onto the table 16, that an address may be applied thereto. It is sometimes desired that the papers may be delivered from the machine in a quarter or eighth folded condition without applying this address and therefore in order to render this operation possible, the address applying mechanism may be rendered inactive without affecting the operation of the remaining portion of the machine. This may be accomplished in any desired or suitable manner but preferably in a manner which will now be described, reference being now had more particularly to Figs. 1 and 13. The shaft 65 which controls the operation of the address applying mechanism and the stamper 83 receives its motion from the shaft 31 through the medium of the gear 46 which meshes with a gear 145 and this gear in turn meshes with a gear 146, which is mounted loosely on the shaft 65 and is provided with a clutch face 147. A clutch element 148 is secured to the shaft 65 so as to be adjusted longitudinally thereon and is movable into and out of engagement with the clutch face 147 of the gear 146. It will thus be seen that when the clutch element 148 is adjusted into operating position with respect to the clutch face 147 and secured in this position, the gear 146 will be locked to the shaft 65 and when this gear 146 is rotated the shaft 65 will be operated to actuate the address applying mechanism already referred to. If, now, it is desired to render the address applying mechanism inactive all that is necessary is to release the gear 146 with respect to the shaft 65 and this may be accomplished by unfastening the clutch element 148 and adjusting it on the shaft 65 so that it will be in an operating position with respect to the clutch face 147. As the gear 146 will then be free to rotate, it will be apparent that the operation of the remaining mechanism which is controlled by the gear 146 will not be interfered with.

It may be desired to apply a wrapper to the papers after they have been folded into an eighth fold and in order that the wrapper may be thus applied and sealed before the paper is delivered from the machine, simple

and efficient mechanism for accomplishing this result will now be described, reference being had more particularly to Figs. 1, 4 and 5. The wrapper designated generally by the reference numeral 159 is supplied to the machine from any suitable source, preferably from a roll mounted in any convenient position on the machine and this wrapper passes between rolls 160 (see Fig. 1) which receive their motion from the gear 41 on the shaft 38 which gear meshes with a gear 161 and this gear in turn with a gear 162 on one of the rolls 164 and the gear 162 meshes with a gear 163 on the other of the rolls 160. A second pair of rolls 164 is spaced from the pair 160 and the wrapper 159 passes between these rolls. The rolls 164 also receive their motion from the gear 41 through the medium of a gear 165 with which the gear 41 meshes and the gear 166 with one of the rolls 164 which meshes with the gear 165. A gear 167 is provided on the other of the rolls 164 and meshes with said gear 166. The pairs of rolls 160 and 164 are arranged on opposite sides of the shafts 38, 43, and mounted to rotate with one of the shafts, preferably the shaft 38, (see particularly Fig. 10) is a roll 168 which is provided with spaced bearings 169 in its periphery and these bearings are provided with openings 170 opening through the periphery of the roll. A similar roll 171 is provided on the shaft 43 above the roll 168 with its periphery in close proximity with the periphery of the roll 168. This roll 171 is provided with sockets 172 opening through its periphery within which sockets are arranged perforators 173 and elastic or yielding members 174 are also provided in the sockets 172 on each side of the perforators. These elastic members 174 are of a height to normally stand flush with the perforating edges of the perforators and are so arranged that when the perforators assume positions with respect to the roll 168 to enter the apertures or recesses 170, they will be depressed so as to permit the active edge of the perforators to come into contact with the wrapper which passes between the rolls 168, 171, to perforate the wrapper. When the perforators pass away from the wrapper elastic members will expand and thereby serve as a means for stripping or ejecting the wrapper from the edge of the perforator.

From the rolls 164 the wrapper 159 may pass through another pair of rolls 175, which latter receive their motion from the gear 145 through the medium of a gear 176 with which the gear 145 meshes and which gear 176 is secured to one of the rolls 175 and meshes with a gear 177 on the other of the rolls 175. From the rolls 175 the wrapper passes between endless conveyors or tapes 178, 179, (see also Fig. 3) and is conveyed into a position across the path of movement

of the paper when it has been given a quarter fold and is passing between the pairs of rolls 84, 85. A support or guide 180 (see Fig. 5) is arranged above the pair of rolls 86 and is provided with a slot or opening 181, the edges 182 of the support 180 adjacent the slot 181 being curved or deflected downwardly as shown, to serve as a means for properly guiding the paper and wrapper into the bite of the rolls 86. This slot 181 is arranged in line with the bite of these rolls 86 and the endless conveyers 178, 179 are so arranged that the wrapper which is conveyed thereby will be moved upon the surface of the support 180 to extend across the slot 181 so that as the paper is being ejected from the pairs of rolls 85 the folded edge of the paper will strike the portion of the wrapper extending across the slot 181 and carry the wrapper with it between the rolls 86. The wrapper is severed from the strip in any suitable manner, preferably by imparting a more rapid degree of rotation to the rolls 175 than to the rolls 164, as will be understood. It will thus be seen that after the paper is given a quarter fold it will strike the wrapper and carry the wrapper with it into a position to be folded with the paper by the second folding knife or blade 138 and will be deflected thereby into the bite of the rolls 106, 86. As the wrapper and folded paper pass between these latter rolls, and if the guide 107 is permitted to remain in the position shown in full lines in Fig. 5, the paper and wrapper will be conveyed away from the machine in the manner which has already been described, and the paper although it is supplied with a wrapper will not be sealed, that is to say, the wrapper will simply encompass the paper without being pasted or sealed. In order to overcome this objection and to seal the wrapper after it has been thus applied to the paper, suitable sealing mechanism is provided which will now be described, reference being had more particularly to Figs. 4 and 5. Arranged below the pairs of rolls 86 is a paste pot 183 across which a roll 184 is journaled and to which paste is delivered by means of a roll 185. Rotary motion is imparted to the roll 185 by means of a gear 186 on the shaft 187 of the roll with which gear 186 a gear 188 on a shaft 189 meshes, and rotary motion is imparted to this shaft 189 through the medium of a gear 190 in a manner which will hereinafter be explained. A paper receiving pocket designated generally by the reference numeral 191 in Fig. 11 preferably comprises a plurality of spaced forks or pairs of guides 192 and the extremities of the body portion of the pocket are provided with trunnions 193 journaled in arms 194 and these arms 194 are in turn supported by a shaft 195 (see also Fig. 2). The forks or pairs of guides 192 are of a

length so that the pocket formed thereby will be of a depth substantially equal to the width of the folded paper which is delivered thereinto in a manner to be described and so that when the paper is seated in this pocket, together with the wrapper, one edge of the wrapper will project for some distance beyond the paper and the edge of the pocket to form a flap to be sealed down upon the paper. The pocket thus formed is rocked on its trunnions 193 in the bearings in the arms 194 by means of a cam 196 on a shaft 197 (see also Fig. 1) and this cam 196 operates on an anti-friction roller 198 on an arm 199 which is provided with a bifurcated extremity 200 standing astride of the shaft 197. The other extremity of the arm 199 is pivotally connected to an ear or extension 201 projecting from the pocket 191 (see Fig. 11), so that as the shaft 197 is rotated the cam 196 will through the medium of the arm 199 rock the paper pocket about its point of pivotal support.

In order to direct the paper into the pocket 191, the guide 107 must be shifted from the position shown in full lines in Fig. 5 to that shown in dotted lines so as to move the surface 110 to a position that the paper will not pass thereover. This is accomplished in any suitable manner and a simple and efficient means for effecting this adjustment will now be described. The guide 107 is provided adjacent one end with upwardly projecting spaced ears or lugs 203 (see Figs. 5 and 6) between which an arm 204 on the shaft 137 projects, and the shaft is provided with a handle 205 (see Fig. 2) arranged on the outside of the machine and in a convenient position for the operator, by means of which the shaft may be rocked. The guide 107 is provided with a curved face 206 adjacent the roll 106, which face when in the position shown in dotted lines is adapted to be engaged by the edge of the paper so that the paper will be deflected when it strikes the face between the rolls 106 and 208. It will thus be seen that the shaft 137 may be rocked by means of the arm 205 at will so as to adjust the guide 107 so that the curved face 206 will be disposed across the path of the advancing movement of the paper as it passes from the between the rolls 106, 86. The guides 136 are also adjusted to the position shown in dotted lines in Fig. 5 so as to be moved out of the way, to permit the above referred to adjustment of the guide 107. As the paper rides over the face 206 of the guide, and assuming the pocket to be in the position shown in full lines in Fig. 5, the paper together with the wrapper will be directed into the pocket. In order to advance the papers as they pass from between the rolls 106, 86, and to force them into the pocket 191, the roll 208 is provided which cooperates with the roll 106

and this roll 208 is preferably of a segmental shape and is mounted on the shaft 109. By the provision of this segmental-shape roll 208 it is possible to arrange the pocket 191 in such a position that the extremities of the forks or guides 192 thereof will be disposed in close proximity to the periphery of the roll 106 and the cut-away portion of the roll 208 will permit the pocket to be freely oscillated and the ends of the forks or guides will not strike the rolls.

Arranged adjacent the pulley 115 and also adjacent the roll 208 is a roll 209 which is also disposed in close proximity to the segmental roll 208 so that the latter will co-operate therewith. When the pocket is in a position to receive the paper, the roll 208 will co-operate with the roll 106 to force the paper and the wrapper thereinto. When the paper and wrapper have been seated in the pocket, the free edge of the wrapper will project beyond the pocket and also beyond the top edge of the paper. After this operation has been completed the can 196 will have assumed a position with respect to the anti-friction roller 198, to shift the arm 199 and rock the pocket about its point of pivotal support so as to bring the free extremities of the forks or guides 192 into the position as shown in dotted lines in Fig. 5 to present the paper to the bite of the rolls 208, 209.

During the movement of the pocket from the time in which it receives the paper and into a position so that the paper will be directed into the bite of the rolls 208, 209, the high portion of the roll 208 will be in contact with the flap of the wrapper and while the pocket is being moved into the position which it assumes when the paper is to be ejected, the roll 208 will serve as a means for turning the flap of the wrapper over the edge of the paper and against the body portion of the wrapper, adhesive material being applied to the wrapper previous to this folding movement in such manner as will be presently described. It will be apparent that when the parts have assumed this position, and the paper is ejected from the pocket, the flap edge of the wrapper and the paper will be forced into the bite of the rolls 208, 209, and these rolls will not only serve as a means for sealing down the flap but will also force the wrapped paper between the adjacent runs of the conveyers 112, 113, to be conveyed away by these conveyers and delivered from the machine in the manner as already set forth.

The manner of applying the paste or adhesive material to the body portion of the wrapper for sealing down the flap will now be described. Pivottally supported, preferably by one extremity and adjacent opposite sides of the paste tank 183, reference being

had more particularly to Figs. 4 and 5, are spaced arms or supports 210 in the upper extremities of which are upwardly opening sockets or bearings 211 and a shaft 212 is journaled in these bearings to extend across the paste tank. The shaft 212 is arranged in close proximity to the distributing roll 184 and mounted upon the shaft 212 for rotation therewith are ductor rolls 213 which are adapted to be moved into and out of contact with the distributing roll 184 when the arms or supports 210 are rocked about their points of pivotal support 214 and also to move the ductor rolls 213 into engagement with the body portion of the wrapper on the paper which is in the pocket. These ductor rolls 213 are preferably spaced from each other as shown more clearly in Fig. 4 so as to move into engagement with the wrapper between the forks or spaced guides 192. The ductor rolls 213 are adapted to be oscillated from the shaft 197 and for this purpose there is provided on the shaft 197 a cam 215 which co-operates with an anti-friction roller 216 on an arm 217. One extremity of the arm 217 is bifurcated as at 218 so as to stand astride of the shaft 197 and the other extremity of the arm is connected to an arm or extension 219 which latter is connected with the supports 210 so that when the shaft 197 rotates the cam 215, the latter will reciprocate the arm 217 and cause the supports 210 and ductor roll 213 to move into engagement with the distributing roll 184. The movement of the ductor rolls 213 in the opposite direction or away from the distributing roll 184 into engagement with the wrapper may be effected in any desired or suitable manner but preferably through the medium of an elastic member 220 which surrounds a bar or rod 221, one extremity of which is connected as at 222 with the supports 210 and preferably on the side opposite to the side on which the arm 217 is connected. The other end of this bar or rod 221 passes through a suitable guide 223 and is threaded as shown for the reception of a nut or collar 224. This elastic member 220 is preferably arranged between the guide 223 and a collar 225 connected with the bar or rod so that the tension of the elastic member 220 tends normally to move the ductor rolls 213 toward the pocket 191. By the provision of the elastic member 220 for moving the ductor rolls in this direction it will be apparent that the rolls will be yielding and will readily assume positions to accommodate papers of varying thicknesses which are deposited into the pockets. In order to adjust the movement of the ductor rolls under the influence of the cam 215, a pin and slot connection is provided between the arm 217 and the projection 219 of the supports 210. The slot 226 is provided in the extension 219 and the pin 227 is pro-

passes through the end of the arm 217 and through the slot 226. Thus it will be seen that by loosening the pin 227 it may be adjusted in the slot to raise and lower the end 5 of the arm 217 with respect to the end or extension 219 and after being thus adjusted may be secured in position.

After the paste has been applied to the wrapper and the pocket 191 adjusted in the 10 manner already described, that is, from its receiving to its delivering position, the papers are removed from the pocket as described. It is advisable, however, to provide means whereby the papers may be elevated 15 or partially ejected from the pocket after the paste has been applied to the wrapper and the flap turned over so as to force the papers into the bite of the rolls 208, 209. Any suitable means may be provided for 20 this purpose but a simple and efficient means will now be described, reference being still had to Figs. 4 and 5. Pivotaly supported by the shaft 195 are ejector fingers 228 any number of which may be provided but in 25 the present exemplification two only are shown. These ejector fingers are spaced from each other and are preferably connected by means of a hub 229, which latter is sleeved upon the shaft 195 to oscillate 30 thereabout. The forward extremities of the fingers 228 are preferably curved as at 230 to conform to the contour of the lower edge of the paper and project across the bottom of the pocket into the spaces between the 35 forks or guides 192 and are adapted to normally rest or stand adjacent the bottom of the pocket, and in positions to receive the papers so that the lower edge thereof will rest upon the fingers when the paper is in 40 the pocket. In order therefore to eject the paper from the pocket all that is necessary is to oscillate or move the fingers 228 about the support and with respect to the pocket, at the proper time. This may be accomplished 45 by means of a cam 230 on the shaft 197 and this cam is preferably of the box type so as to impart a positive movement of the fingers or ejectors 228 in both directions. An arm 231 is pivotally connected 50 by one extremity as at 232 to an ear or extension 233 on the hub 229 and the other extremity of the arm is bifurcated as at 234 to stand astride of the shaft 197. An anti-friction roller 235 is supported by the arm 231 and projects into the groove in the cam. 55 Thus it will be seen that when the cam is rotated the anti-friction roller 235 will travel in the groove thereof and this movement will cause a reciprocating movement 60 of the arm 231 and a rocking movement of the fingers or ejectors 228. The cam 230 is so disposed with respect to the cam 196 that the fingers or ejectors 228 will not be oscillated about their points of pivotal support 65 until the pocket 191 has assumed the proper

position with respect to the rolls 208, 209, that the paper when ejected by the fingers 228 will be forced into the bite of these rolls 208, 209.

In order to limit the forward movement 70 of the ductor rolls 218 or their movement in a direction toward the pocket 191, there may be provided a lip or projection 236 on an extension 237 of the paste pot 183 (see also Fig. 9) with which an ear or extension 238 on the support 210 is adapted to coöperate, and this ear or extension 238 is adapted to strike the projection 236 for arresting the movement of the support 210. The support 210 is preferably provided with an ear or extension 238 projecting from both sides thereof so that the support may be used on either side of the machine as will be understood.

Motion is imparted to the shaft 197 and 85 to the rolls 106, 208, 209 and 185 in any suitable manner, preferably in the manner which will now be described, reference being had more particularly to Figs. 1, 2 and 3. On the shaft 239 of the roll 106 is a gear 240 which meshes with an idler 241 and this gear in turn meshes with a gear 242 on the shaft 197. The gear 100 which is connected with the shaft 243 of one roll of the pair 86 meshes with an idler 244, and this gear in turn meshes with a gear 245 on the shaft 109 of the roll 208. This gear 245 meshes with an idler 246 which in turn meshes with a gear 247. Thus it will be seen that when the gear 100 is rotated motion will be imparted therefrom to the gear 247 and as this gear 247 is connected with the gear 241 the latter will be rotated and will impart motion to the shaft 197 to operate the cams 196, 215 and 230. The gear 247 also meshes with 90 a gear 248 which is connected to the shaft 249 (see also Fig. 5) of the roll 209 whereby motion will be imparted to the roll. The gear 241 also imparts its motion to the shaft 189 to which the gear 188 is secured, through 95 the medium of the gear 190 on the shaft 189 and with which gear the gear 241 meshes. It will thus be seen that all of these parts receive their motion from the shaft 29.

The rolls 106, 209 may be mounted in 100 yielding bearings and the roll 106 may be adjusted with respect to the coöoperating rolls 86, 208 in any desired or suitable manner, preferably by means of an arm 250 arranged on the outside of the machine in a 105 convenient position that ready access may be had thereto.

In the event that it is not desired to apply 110 a wrapper to the paper when it is to be folded in an eighth fold, the wrapper supplying mechanism may be thrown out of operation by adjusting or releasing the gear 37 on the shaft 38 in the manner already described and when this wrapper supplying 115 mechanism is thus rendered inactive it is 120 125 130 135

advisable that the ductor roll be rendered inactive so that it will not oscillate back and forth to come into contact with the paper in the pocket. This may be accomplished by 5 adjusting the nut or collar 224 on the threaded extremity of the bar or rod 221 until it is in engagement with the guide 223 and this will hold the anti-friction roller 216 on the arm 217 in a position that it will 10 not be affected by the cam 215. This adjustment will in no way affect the oscillation of the pocket 191 or the operation of the ejector fingers 228.

In the event that it is desired to deliver 15 the papers from the machine in a quarter-fold, it is advisable that the operating mechanism for oscillating the pocket 191, actuating the ejector fingers 228 and for oscillating the ductor rolls 213, be rendered inactive and for this purpose the gear 242 (see 20 particularly Fig. 1) is mounted loosely upon the shaft 197 and is provided with a clutch face 251. A clutch element 252 is provided on the shaft 197 to cooperate with the clutch 25 face 251. This clutch element 252 is adapted for longitudinal adjustment on the shaft 197 and is secured thereto for rotation therewith. Thus it will be seen that the clutch element 252 may be shifted into or out of 25 engagement with the clutch face 251 so that the gear 242 will be locked to or released with respect to the shaft 197 and when released the shaft 197 will remain idle.

What is claimed as new is—

35 1. In a folding machine of the character described, the combination of means for folding the articles, means for imparting another fold to the article after it has been folded by the first said means, conveying 40 mechanism common to both said folding means for receiving and conveying away the folded article, and means controllable at will whereby the article may be delivered directly to the said conveying mechanism in 45 either stage of its folded condition.

2. In a folding machine of the character described, the combination of means for folding the article, means for imparting to the article another fold as it comes from the 50 first said means, conveying mechanism in proximity to the top of the machine for receiving the folded article and conveying it across the top of the machine and above the folding means, said conveying mechanism being supported by the machine, a common source of power for actuating both recited folding means and the conveyer, means whereby the second recited means may be rendered inactive at will, while the first recited means and the conveyer remain active, and means whereby the article may be presented to the conveyer in any stage of its folded condition.

3. In a machine of the character described, the combination of address applying

mechanism, means for folding the article as it comes from the said mechanism, means for imparting to the article another fold after it has been folded by the first said means, and means for rendering the second recited means and the address applying mechanism active or inactive without interfering with the operation of the first recited means.

4. In a machine of the character described, the combination of address applying mechanism, means for folding the article as it comes from said mechanism, means for imparting to the article another fold after it has been folded by the first recited means, a common source of power for actuating both of the said means and the address applying mechanism, and means under the control of the operator for rendering the address applying mechanism and the second recited means active or inactive at will while the first recited means remains active.

5. In a machine of the character described, the combination of addressing mechanism, folding mechanism embodying means for giving to the article a plurality of folds as it comes from the addressing mechanism said folding mechanism being adapted to be rendered inactive, and means for ejecting the article as it comes from the addressing mechanism and independently of the folding mechanism while the latter is inactive.

6. In a machine of the character described, the combination of addressing mechanism, folding mechanism embodying means for giving to the article a plurality of folds as it comes from the addressing mechanism said folding mechanism being adapted to be rendered inactive, means for receiving and conveying away the article from the folding mechanism, and means for ejecting the article from the addressing mechanism and independently of the conveying means and of the folding mechanism while the latter is inactive.

7. In a folding machine, the combination of folding mechanism embodying means for giving to the article a plurality of folds, mechanism for supplying to the partially folded article a wrapper to be folded with the article, paste applying mechanism for the wrapper, means for turning and sealing down the wrapper flap, and means for rendering the wrapper supplying and the paste applying mechanisms inactive while the folding mechanism remains active.

8. In a machine of the character described, the combination of address applying mechanism, folding mechanism for giving to the article a plurality of folds, means for supplying to the article a wrapper, paste applying means for the wrapper, means for turning and sealing the wrapper flap, and means for rendering the wrapper supplying

and the paste applying means inactive while the address applying mechanism and the folding mechanism remain active.

9. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, and means for rendering the second recited folding means and the wrapper supplying and pasting means inactive while the address applying mechanism and first recited folding means remain active.

10. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, and means for rendering the address applying mechanism, the second recited folding means and the wrapper supplying means and pasting means inactive while the first said folding means remains active.

11. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, and means for rendering the address applying mechanism, the wrapper supplying means and the paste applying means inactive while both of the said folding means remain active.

12. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, and means for rendering any one or more of said means and mechanism inactive at will while the other of said means and mechanisms remain active.

13. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, a source of power common to all of the operating parts for actuating the same,

and means for rendering any one or more of said means and mechanism inactive at will while the other of said means and mechanisms remain active.

14. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, means for rendering any one or more of said means and mechanism inactive at will while the other of said means and mechanism remain active, and means for ejecting the article as it comes from the address applying mechanism independently of the folding and wrapping means and while the latter is inactive.

15. In a machine of the character described, the combination of address applying mechanism, means for folding the article as it comes from said mechanism, means for giving to the folded article another fold as it comes from the first said folding means, means for supplying a wrapper to the article, means for pasting and sealing the wrapper, means for rendering any one or more of said means and mechanism inactive at will while the other of said means and mechanisms remain active, means for ejecting the article as it comes from the address applying mechanism independently of the folding and wrapping means, and while the latter is inactive, and a source of power common to all of the operating parts for actuating the latter.

16. In a folding machine of the character described, the combination of means for folding the article, means for giving to the article another fold as it comes from the first said means, means for supplying to the partially folded article a wrapper, means for applying paste to and sealing the wrapper about the article embodying a shiftable carrying pocket adapted to receive the article and wrapper and carry them to a position to be conveyed away, means for shifting said pocket, and means for rendering the wrapper supplying and sealing means active or inactive at will while the remaining mechanisms remain active, and without interfering with the operation of the latter.

17. In a folding machine of the character described, the combination of means for folding the article, means for giving to the article another fold as it comes from the first said means, means for supplying to the folded article a wrapper, means for sealing the wrapper about the article embodying a shiftable carrying pocket adapted to receive the article and wrapper and carry them to a position to be conveyed away, means controllable at will for diverting the article and

the wrapper from the pocket, and means for rendering the wrapper supplying and sealing means active or inactive while the remaining mechanisms remain active.

- 5 18. In a folding machine of the character described, the combination of means for folding the article, means for giving to the article another fold as it comes from the first said means, means for supplying to the 10 partially folded article a wrapper, means for sealing the wrapper about the article embodying an oscillating carrying pocket adapted to receive the article and wrapper and carry them to a position to be conveyed 15 away, means controllable at will for diverting the article and the wrapper from the pocket, means for rendering the wrapper supplying and sealing means active or inactive while the remaining mechanisms remain active, and a source of power common to all of the operating parts for actuating the latter.

19. In a folding machine of the character described, the combination of means for 25 folding the article, means for giving to the article another fold as it comes from the first said means, means for supplying to the article a wrapper, means for incasing the article in the wrapper embodying a shiftable pocket for receiving the article and wrapper, means for applying to the wrapper paste for sealing the flap thereof, means for shifting the pocket to carry the article and wrapper to a position to be conveyed away, 30 means for projecting the article from the pocket, and means for rendering the wrapper supplying means and the paste applying means inactive while the remaining operating parts remain active.

- 40 20. In a folding machine of the character described, the combination of means for folding the article, means for giving to the article another fold as it comes from the first said means, means for supplying to the 45 article a wrapper, means for incasing the article in the wrapper embodying an oscillating pocket for receiving the article and wrapper, means for applying to the wrapper paste for sealing the flap thereof, means for oscillating the pocket to carry the article and wrapper to a position to be conveyed away, means for projecting the article from the pocket, and means for rendering the wrapper supplying means and the paste applying means inactive while the remaining operating parts remain active, and a source of power common to all of the operating parts for actuating the latter.

21. In a folding machine of the character 50 described, the combination of means for folding the article, means for giving to the article another fold as it comes from the first said means, means for supplying to the article a wrapper, means for incasing the article in the wrapper embodying a shiftable

55 pocket for receiving the article and wrapper, means for applying to the wrapper while in said pocket paste for sealing the flap thereof, means for shifting the pocket to carry the article and wrapper to a position to be conveyed away, a conveyer for receiving the article from the pocket, means for projecting the article from the pocket after the paste has been applied and the pocket shifted, and means for rendering the wrapper supplying means and the paste applying means active or inactive while the remaining operating parts remain active.

22. In a folding machine of the character described, the combination of means for 60 folding the article, means for giving another fold to the article, a carrying pocket for receiving the article from the second said means and carrying it to a position to be conveyed away, means for extracting the article from the pocket when in such position, means for rendering the second recited folding means inactive while the first recited folding means remains active, and means for conveying the article past the said pocket 65 when the second recited means is inactive.

23. In a folding machine of the character described, the combination of means for 70 folding the article, means for giving another fold to the article, a carrying pocket for receiving the article from the second said means and carrying it to a position to be conveyed away, means for extracting the article from the pocket when in such position, means for shifting the pocket, means for 75 rendering the second recited folding means inactive while the first recited folding means remains active, and means for conveying the article past the said pocket when the second recited means is inactive, the last 80 said means embodying a guide shiftable into one position to direct the article into the pocket and into another position to direct the article past the pocket.

24. In a folding machine of the character 85 described, the combination of means for folding the article, means for giving another fold to the article, a carrying pocket for receiving the article from the second said means and carrying it to a position to be 90 conveyed away, means for extracting the article from the pocket when in such position, means for shifting the pocket, means for rendering the second recited folding means inactive while the first recited folding means 95 remains active, means for conveying the article past the said pocket when the second recited means is inactive, the last said means embodying a guide shiftable into one position to direct the article into the pocket and 100 into another position to direct the article past the pocket, and means for shifting said guide at will.

25. A folding machine of the character 105 described, embodying folding mechanism,

- the latter including a folding knife or blade, means for receiving the article from said folding mechanism and carrying it to a position to be delivered from the machine, means for directing the article from the folding mechanism to the said receiving means, embodying means for directing the article past the said receiving means when the said folding blade is rendered inactive, 10 means for controlling the said directing means, means for rendering the folding blade inactive at will, and a guide for directing the article to the second recited means when the folding blade is rendered inactive. 15
26. A folding machine of the character described, embodying folding mechanism, the latter including a folding knife or blade, means for receiving the article from said folding mechanism and carrying it to a position to be delivered from the machine, means for directing the article from the folding mechanism to the said receiving means, embodying means for directing the article past the said receiving means when the said folding blade is rendered inactive, 20 means for controlling the said directing means, means for rendering the folding blade inactive at will, a guide for directing the article to the second recited means when the folding blade is rendered inactive, and means whereby the said guide may be rendered active and inactive when the said folding blade is rendered respectively inactive 25 and active.
27. In a machine of the character described, the combination of folding mechanism to fold an article, means for supplying to the article a wrapper, means for incasing the article in the wrapper and embodying a carrying pocket for receiving the article and wrapper and carrying them into a position to be conveyed away, means for directing the article from the folding mechanism to the pocket when the wrapper supplying means is active or inactive and embodying means for directing the article past the pocket when the folding mechanism is rendered inactive, means for rendering the folding mechanism inactive, and means for rendering the wrapper supplying means inactive while the third recited means remains active. 45
28. In a machine of the character described, the combination of folding mechanism to fold an article, means for supplying to the article a wrapper, means for incasing the article in the wrapper and embodying a carrying pocket for receiving the article and wrapper and carrying them into a position to be conveyed away, means for directing the article from the folding mechanism to the pocket when the wrapper supplying means is active or inactive and embodying a 55 shiftable guide also adapted for directing
- the article past the pocket when the folding mechanism is rendered inactive, means for rendering the folding mechanism inactive, means for rendering the wrapper supplying means inactive while the third recited means 70 remains active, and means for shifting said guide at will. 75
29. A machine of the character described embodying a shiftable pocket for receiving the article, means for directing the article into the pocket embodying delivery rolls disposed adjacent the mouth of the pocket, an additional roll coöperating with one of the first recited rolls for gripping and extracting the article from the pocket when the latter is shifted from its receiving to its delivering position, the edge of the pocket at its mouth being disposed in close proximity to the rolls, a portion of the periphery of one of the rolls being cut away to permit a free 80 movement of the pocket, means for shifting the pocket from one of its positions to its other position, and an oscillating arm for ejecting the article from the pocket. 85
30. In a machine of the character described, the combination of a shiftable pocket for receiving the article and conveying it into a position to be conveyed away, a pair of rolls arranged so that their bite will deliver an article directly into the pocket 90 when the latter is in a receiving position, an additional roll coöperating with one of the first said rolls and arranged with respect thereto so that the article will be gripped by the last two recited rolls to be extracted 95 from the pocket, one of said rolls being arranged intermediate the other rolls and having a portion of its periphery removed, means for shifting the pocket to present the article to the bite of the extracting rolls, 100 and an oscillating arm for projecting the article from the pocket and into the bite of the extracting rolls. 105
31. In a machine of the character described, the combination of means for folding the article, means for supplying a wrapper thereto, a shiftable pocket for receiving the article and wrapper, a pair of rolls for delivering the article and wrapper into the pocket, an additional roll coöperating with one of the first said rolls and acting therewith for turning and sealing down the wrapper flap, shiftable means for applying paste to the wrapper while in the pocket, means for shifting the pocket to present the article 110 to the bite of the last recited rolls to be extracted thereby, and means for projecting the article from the pocket and into the bite of the extracting rolls, one of the said rolls having a portion of its periphery removed. 115
32. In a machine of the character described, the combination of means for folding the article, means for supplying a wrapper thereto, a shiftable pocket for re- 120 125 130

- ceiving the article and wrapper, a pair of rolls for delivering the article and wrapper into the pocket, an additional roll coöperating with one of the first said 5 rolls and acting therewith for turning and sealing down the wrapper flap, shiftable mechanism adapted to be moved into engagement with the wrapper while in the pocket, for applying paste to the wrapper, means 10 for shifting the pocket to present the article to the bite of the last recited rolls to be extracted thereby, means for projecting the article from the pocket and into the bite of the extracting rolls, and means for rendering 15 the wrapper supplying and paste applying means inactive while the remaining mechanisms remain active.
33. In a machine of the class described, the combination of addressing mechanism, 20 mechanism for folding the article, mechanism for imparting to the article another fold as it comes from the first recited folding mechanism, wrapper-supplying mechanism, mechanism for delivering the article from the machine after it leaves the addressing mechanism and independently of the folding and 25 the wrapper-supplying mechanisms while

the last two recited mechanisms are inactive, and means whereby any one or more of said mechanisms may be rendered inactive at will 3. while the remaining mechanisms remain active.

34. In a machine of the class described, the combination of addressing means including an address applying mechanism, mechanism for folding the article, mechanism for imparting to the article another fold as it comes from the first recited folding mechanism, wrapper supplying mechanism, and means for conducting the article through the 40 address applying mechanism independently of the other said mechanisms or through one or more of the latter mechanisms independently of the address applying mechanism, at will. 45

In testimony whereof I have signed my name to this specification, in the presence of two subscribing witnesses, on this 13th day of February, A. D. 1911.

JOSEPH TOMLINSON.
